UNITED STATES PATENT OFFICE.

FRANK GERACI, JR., AND THOMAS GERACI, OF WASHINGTON, DISTRICT OF COLUMBIA.

PLAYING CARDS.

Application filed October 5, 1925. Serial No. 60,530.

To all whom it may concern:

Be it known that we, FRANK GERACI, Jr., and THOMAS GERACI, citizens of the United States, and residents of Washington, in the 5 District of Columbia, have invented certain new and useful Improvements in Playing Cards, of which the following is a specification.

The invention is a card game in which the 10 cards represent race horses having indicated ratings and winning points in respect to a series of races of different distances, such as one-half mile, three-fourths mile, etc., the said cards preferably bearing also other indications as to the number of points for 15 second and third place, and further indications relating to a Derby race, all of which will be clear from the following description.

In the accompanying drawings we show, 20 as an example in Fig. 1, four cards of the pack, which consists of fifty-four cards.

Fig. 2 represents a score card. Two of the 25 cards of Fig. 1 are representative of horses "My Girl" and "Plucky" having the two highest ratings respectively 100 and 99 for the one-half mile race, and the other two cards representing the horses named "Hold On" and "Cloudy" have low ratings respectively 47 and 48 for the half-mile race.

30 These cards are illustrated as representative of the general idea upon which the game is based, it being understood that the other cards of the pack, of which, as just stated, there are fifty-four, represent other horses 35 with other ratings for the different races.

Referring more particularly to the character of the cards and taking the one marked "My Girl" as an example, it will be noted that the lengths of the seven races that can 40 be placed are indicated in the left-hand column, i. e., $\frac{1}{2}$ M., $\frac{3}{4}$ M., and so on up to a distance of two miles, indicated by the symbol 2 M. Opposite each distance indication and in the column at the right thereof under 45 the heading "Rating" are the ratings for this particular horse for each of the distances noted, that is to say, for the one-half mile race ($\frac{1}{2}$ M.) this horse has a rating of 100. For the $\frac{3}{4}$ M. race the rating of this horse 50 drops to the figure 47, and so on for each of the races a rating is given for this horse, the rating for two miles (2 M.) being 52.

55 These ratings represent the value of the card for each particular race. That is to say, if the one-half mile race is being run

and a player holds and plays this card which has the high value or rating of 100, this player would take the trick into which this card is thrown, but in playing this card and taking this trick the player would be credited with only one point. In other words, by playing this card the player would be playing safe, but at the expense of receiving the lowest possible number of points.

Each card therefore has a column of figures under the heading "Win points," which figures represent the number of points the player will be credited if he takes a trick with this card. For instance, if in playing the two mile race (2 M.) this card with a 60 rating of 52 is the highest value played into the trick, the trick belongs to this player and he would be credited with 49 points, because the card has this indication of 49 in the column just mentioned, i. e., in the 65 column headed "Win points."

Each card has also a column headed "2nd place" and a column headed "3rd place," the 70 numbers in which indicate the credits that this card will give the player if its rating or value is such as to be the second or third highest in the trick.

Each card also has a series of indications 75 under the general heading "Derby," there being one of these indications in each of the columns "Rating," "Win points," "2nd place," and "3rd place," the last three indications being in the form of percentages.

In playing the game, all cards of the pack are shuffled and dealt to the players, of 80 which they may be, say, from four to eight. Each player is dealt, say, five cards, and the remainder of the pack is placed face downward on the table.

Each player at the outset will be charged 85 with, say, 150 points, and a score sheet will be made up like that shown in Fig. 2, but in blank, with names of the players and with columns of spaces for the entry of the points won at each of the seven races. Also a 90 column for the sum total number of points won. Also a column for the Derby race and a column for the total points won. Also spaces at the foot of the score card in which 95 may be entered the total of points won by 100 the several horses in each race.

Those cards of the pack which remain 105 after the deal and are placed face down on the table represent those horses which are not running in the race and the knowledge 110

as to these horses, their ratings, etc., is of course not known to any of the players, thus introducing into the game same element of uncertainty and chance, as in any card game, 5 wherein certain cards of the pack lie in the so called "widow."

The first race to be run being the one-half mile ($\frac{1}{2}$ M.), each player will examine his "hand" and select therefrom the card or 10 horse which he thinks will have the best chance of coming in ahead, i. e., having the highest rating, and at the same time will give him the highest number of winning points. The player having exercised his 15 judgment, based on his review of his cards, will lay the selected card face down on the table. Each player having in like manner selected and placed face down the card which he believes gives him the best chance 20 of winning the trick with the highest number of points, the selected cards are then turned face up and compared, and the card representing the horse having the highest rating is the card of highest value and this 25 takes the trick and therefore wins the race, and consequently an entry is made on the score card opposite the winning player's name of the number of points which are found on the winning card in the column 30 headed "Win points" opposite the designation of this particular race, viz, $\frac{1}{2}$ M.

It will be seen that a player has the choice of playing safe, if he has a card representing a horse with a high rating, as the horse "My 35 Girl," the rating of which for $\frac{1}{2}$ M. is 100, in which event, however, he would win only one point, or he can take a chance of winning the trick with a card representing a 40 poorer horse, having, say, a rating of 69, in which event he would win 32 points.

The player therefore has the element of chance to consider and if he can win with a card representing a horse with a low rating for the particular distance the race is 45 run, he will gain a large number of points, whereas if he plays a winning card representing a horse with a high rating for this particular distance he will sacrifice his gain, the sure winning horse returning a low number 50 of winning points.

The object therefore is to win the "trick" or the race with a card representing a horse with the smallest possible rating. At the same time the player must be careful not 55 to play the horse with too low a rating because of the chance of losing the trick and never winning.

Besides determining the winning horse for each "deal," or race, the examination of the 60 cards played will also determine, according to the ratings in the column marked "rating," which horse was second and which was third in the race, and corresponding entries from columns "2nd place" and "3rd place" 65 are made on the score card of the number of

points indicated for these places. No record is kept of the ratings of the remaining cards of this deal, it being considered that the horses represented by these cards are in the class usually designated in race course parlance as "also ran." The above operations having been performed, the running of the first race is considered as closed. 70

To run the second race of $\frac{3}{4}$ M., all of the cards are shuffled and procedure like that 75 above described is carried out.

After all the races indicated on the cards, there being seven races in the example given, are run in the manner above described, then the remaining number of points of the original 80 900 with which the players were initially charged in the aggregate, and which have not been already won in the seven races just completed, will constitute the points to be contested for in the grand finale race, or 85 what I term the "Fra-Tom Derby."

This grand finale race is run in the same manner as the previous races, only that the winning horse takes sixty per cent (60%) of the points, the horse coming in second 90 takes 30% and the horse coming in third in the race takes 10% of the points and all the rest of the horses are in the "also ran" class. 95

After the seven races and the "Fra-Tom Derby" all have been run, this will be called 100 a day's racing, all the points that were put up having been disposed of by the winnings of the various horses.

If a new series of races are run, a new score card will be brought out and used for 100 this new series.

Each card will show the colors of the owner and stable, and these colors may be applied in any suitable way, as by colored 105 lines at α .

It will be understood that the ratings of the horses may vary serially from card to card, say, one point, and that the winning points may vary by one unit, that is to say, the ratings may run 100, 99, 98, 97, for the same race from card to card, etc., and the winning points for first place corresponding to these ratings would be 1, 2, 3, 4, etc., though we do not limit ourselves to this respect. 110

It will be noticed by comparing the cards "My Girl" and "Plucky" that for the half mile race ($\frac{1}{2}$ M.) the horse "My Girl" has a rating of 100, whereas "Plucky" for the same race has a rating of 99, and that whereas the horse "My Girl" rapidly loses stamina in running the $\frac{3}{4}$ M. race, and drops in rating to 47, the horse "Plucky" although having a rating of but 99 for the half-mile race, gains in stamina, staying qualities and speed in running the $\frac{3}{4}$ M. race, as indicated by the fact that for this race the rating of this horse is 100. So it will be seen that the rating for each horse varies with the distances the races are run. The rating of a 120 125 130

card for any race is indicated by a number forming one of a regular numerical progression.

It is of course unnecessary to illustrate all of the cards of the pack, it being sufficient to say that the card naturally belonging in the series next to that of "Plucky" would have a rating for the half-mile race of 98 and winning points 3, and place points 0.

10 We claim:

1. A pack of playing cards, each of which represents a race horse, each of said cards having an indication of the rating of the horse and an indication of the number of

15 points which the said card may win.

2. A pack of playing cards, each of which represents a race horse, each of said cards having an indication of the rating of the horse and an indication of the number of 20 points which the said card may win for first, second or third place.

3. A pack of playing cards, each of which represents a race horse, each of said cards having an indication of the rating of the 25 horse, represented thereby, for an indicated distance, and having also an indication of the number of points which said card may win, substantially as described.

4. A pack of playing cards, each of which represents a race horse, each of said cards having indications for distances, indications for ratings corresponding to the different distances, and indications of winning points for each of said distances, substantially as 35 described.

5. A pack of playing cards, each of which represents a race horse, each of said cards having thereon indications of a series of races with an indication of the rating of the 40 horse for each race, and an indication of the number of winning points for each race.

6. A pack of playing cards, each of which represents a race horse, each of said cards having thereon indications of a series of 45 races with an indication of the rating of the horse for each race, and an indication of the number of winning points for each race for first, second and third place.

7. A pack of playing cards, each repre-

senting a horse, each having thereon an indication of the rating of the horse, which ratings vary by a regular numerical progression, from card to card and each having also an indication of the number of winning points, which indications vary in numerical 55 progression, substantially as described.

8. A pack of playing cards, each representing a race horse and each having indications for a plurality of races, with rating indications, one for each race, which ratings 60 differ from each other, and each rating being one of regular numerical progression in respect to the indications on the other cards relating to the same race, each card having an indication of the number of winning 65 points belonging to each rating of said card, each winning point indication different from the other winning point indications of that card and forming one of a regular numerical progression of winning point indications on the other cards, substantially as 70 described.

9. A pack of playing cards, each representing a race horse, each card having a series of race indications thereon with a 75 rating for each race and an indication of winning points for each race, each of said cards having an indication for a Derby race, with the rating of said card for the Derby race, and an indication of the winning percentage, substantially as described.

10. A pack of playing cards, representing race horses, each of which has a series of indications for races of different distances, with a rating for each race differing from 80 the ratings of the other races indicated on said card, the ratings for the different races differing respectively from the ratings of the corresponding races on the other cards, each card also having indications thereon of 85 the different values of the card corresponding to the different ratings indicated thereon, substantially as described.

In testimony whereof, we affix our signatures.

FRANK GERACI, JR.
THOMAS GERACI.
